Attorney.

UNITED STATES PATENT OFFICE.

WILLIAM T. TRUAX, OF BATTLE CREEK, MICHIGAN, ASSIGNOR TO UNITED STATES REGISTER COMPANY, OF BATTLE CREEK, MICHIGAN.

WARM-AIR-REGISTER BORDER.

1,256,489.

Specification of Letters Patent. Patented Feb. 12, 1918.

Application filed February 16, 1916. Serial No. 78,612.

To all whom it may concern:

Be it known that I, WILLIAM T. TRUAX, a citizen of the United States, residing at Battle Creek, in the county of Calhoun and 5 State of Michigan, have invented certain new and useful Improvements in Warm-Air-Register Borders, of which the following is a specification.

This invention relates to warm air register borders, and belongs to that class of 10 cast metal or sheet metal frames that are set into apertures cut in floors or walls to receive them, the office of the border or frame being to support the hot register box at a 15 safe distance from the woodwork of the flooring.

The object of this invention is the production of a register border of the class stated comprising parts of special construction and 20 arrangement, usually of stamped metal, and secured together at their ends by rivets. The construction and arrangements of the parts of this invention are believed to render the manufacture thereof easier and cheaper 25 and more readily assembled than is the case with like borders now in the market.

In the accompanying drawings illustrating 30 this invention, Figure 1 represents a vertical section through a portion of a floor to which this invention has been applied, this invention being shown in section lengthwise, with a register therein. Fig. 2 is a 35 front view of one corner of a register border constructed in accordance with this invention, the parts being shown full size. Fig. 3 illustrates the reverse side of the parts shown in Fig. 2.

Throughout the drawings and the following descriptive explanation, the same letter 40 is employed to refer to the same part.

Considering the drawings, it will be noted that this invention comprises the longitudinal member A, having the inner depressed flange a, and the transverse member B having the depressed inner edge or flange b. It 45 will be understood that a complete border constructed in accordance with this invention has two members A and two members B, and that they are secured together at 50 their ends at right angles with each other. The flanges a and b, form a seat for the top plate C of a warm air register box D, and the register is thereby supported within the border or frame and may not be displaced

sidewise or endwise while in the position set 55 out in Fig. 1.

The transverse members B are provided with the lugs E and e formed integrally with the member by punching portions into projecting positions as shown. The lugs E 60 and e are termed in this description floor lugs, for the reason that they engage the edges of the opening F cut in a floor f at the angles of the opening, and position the border in the opening at the same time holding 65 the hot register box at some distance from the wood flooring.

The longitudinal member A has a depressed outer edge or rim G, and between the outer edge G and the flange a is a relatively raised hollow or dished portion g. In Fig. 2 it will be noted that the hollow raised portion g extends to the end, or nearly to the end of the member. In Fig. 2 it will be seen that the member B also 70 has the outer depressed edge portion H, and the relatively raised hollow portion h between the outer edge H and the flange b. In Fig. 3 it is shown that the hollow raised portion h does not extend to the end of 80 the member, but near the end the member B is flattened, and the rivets J secure the flattened portion K of the member B in the extended hollow raised portion g of the member A, as illustrated in Fig. 3. In 85 other words, the end of one member is passed beneath the end of the other member and is provided with the downwardly projecting floor-engaging lugs E and e. The only riveting necessary is to secure the flat end K 90 of the member B to the member A. Such construction produces a warm air register 95 border, comprising a rectangular frame consisting of duplicate end members and duplicate side members, the outside edge and right-angled corners of the end members having relatively narrow, flat edge portions, and raised portions within such edge portions and extending to them. The raised portions are provided with right-angled corners, 100 and into such corners on the under side of the raised portions, the flat, right-angled end portions of the side members, such as the portion K, are introduced, and riveted as shown. The lugs E and e, which face at 105 right angles with each other and engage the corners of the openings in the floor, are projecting pieces of the portion K. It is not

intended to confine this invention to the precise forms indicated in the drawings, as other and, if desirable, more ornamental configurations may be adopted, the parts 5 still keeping substantially the mechanical shapes and arrangement set forth.

In the operation of this invention, two members A and two members B are secured together to form a rectangular frame or 10 border of the customary character, and the floor is provided with a suitable opening f having right angle corners. When a border constructed in accordance with this invention is set into the floor opening f, the edges 15 of the opening f are engaged near the corners by the floor lugs e and E, and the border cannot become displaced either lengthwise or to one side. A register box D is then 20 placed in the border seating its top plate C upon the depressed flanges a and b, thus holding the top plate and register against displacement to the side or endwise, and supporting the register within the border. Cheap and convenient manufacture is at- 25 tained by this invention as there are practically but two parts which are different one from the other, and neither part requires attachments or adjuncts to be connected with it by some additional operation.

Each member is a single piece of stamped 30 metal.

Having now described this invention, and explained the manner of its use, what I claim is:—

A warm air register border, comprising 35 a rectangular frame consisting of duplicate end members and duplicate side members, the said members having relatively narrow flat edge portions along the inside and outside edges and ends and raised portions 40 within the said edges and extending to them, the said raised portions of the end members having right-angled corners, the said side members having flat right-angled end portions constructed to fit into the under sides 45 of the said right-angled corners of the raised portions of the said end members and being riveted thereto, the said flat end portions of the side members having integral pieces thereof turned downwardly and 50 arranged at right angles with each other to engage an opening in a floor, the openings in the said end portions from which the said pieces are displaced being covered by the said right-angled corners of the said mem- 55 bers.

In testimony whereof I affix my signature.
WILLIAM T. TRUAX.
